CLAIM

I claim the ornamental design for an ice bucket with handle, as shown and described.

DESCRIPTION

FIG. 1 shows a front perspective view of the ice bucket with handle from the frontal elevation.

FIG. 2 shows a top plan view.

FIG. 3 shows a front elevation view.

FIG. 4 shows a right side elevation view.

FIG. 5 shows a left side elevation view.

FIG. 6 shows a rear elevation view; and,

FIG. 7 shows a bottom plan view.
